COMBINED SHADE AND CURTAIN HOLDER

Felix P. Lindsay and Alexander C. Lindsay,
Chickasha, Okla.

Application July 28, 1932. Serial No. 625,462

1 Claim. (Cl. 156—23)

The present invention relates to new and useful improvements in combined shade and curtain holders and has for its primary object to provide, in a manner as hereinafter set forth, a device of this character embodying a novel construction, combination and arrangement of parts through the medium of which said device may be mounted on the upper portion of an upper window sash for vertical movement therewith.

Another very important object of the invention is to provide a combined shade and curtain holder which may be expeditiously adjusted as desired for use on windows of various widths.

Other objects of the invention are to provide a combined shade and curtain holder which will be simple in construction, strong, durable, highly efficient and reliable in use, light in weight, compact, attractive in appearance and which may be manufactured and installed at low cost.

All of the foregoing and still further objects and advantages of the invention will become apparent from a study of the following specification, taken in connection with the accompanying drawings wherein like characters of reference designate corresponding parts throughout the several views, and wherein:—

Figure 1 is a view in front elevation, showing a combined shade and curtain holder in accordance with the present invention mounted in position on a window sash.

Figure 2 is a view in side elevation of the invention.

Figure 3 is a detail view in vertical section, taken substantially on the line 3—3 of Figure 2.

Figure 4 is a top plan view, showing one end portion of the combined shade and curtain holder.

Figure 5 is a detail view in top plan of one of the brackets.

Figure 6 is a detail view in elevation showing one end portion of the telescopic sections before the shade roller and curtain supporting elements are bent outwardly therefrom.

Figure 7 is a view in vertical transverse section, taken substantially on the line 7—7 of Figure 1.

Referring now to the drawings in detail, it will be seen that the embodiment of the present invention which has been illustrated comprises a pair of upwardly inclined metallic brackets 1 of skeleton form having right angularly extending, apertured flanges 2 on their inner ends providing means for mounting the brackets on the upper rail of an upper window sash which is designated by the reference numeral 3. The refer-

ence numeral 4 designates a portion of a window frame of conventional construction in which the sash 3 is slidable.

The brackets 1 are preferably of sheet metal and formed integrally with the upper edge of 60 each bracket is an out-turned, horizontal flange 5 having a longitudinal slot 6 therein. The reference numeral 7 designates telescopic sections which are mounted for adjustment on the brackets 1. To this end, clamps which are designated 65 generally by the reference numeral 8 are provided. The clamps 8 are formed from a single length of flat, resilient metal having an intermediate portion bent or formed to provide an elongated loop or eye 9 for the reception of the 70 sections 7. Each clamp 8 further includes arms 10 extending from the ends of the loop 9 above and below the flanges 5 of the brackets 1. The arms 10 are provided with openings in their free end portions for the passage of a clamping bolt 75 11 for frictionally clamping said arms against the flange 5. The bolt 11 passes through the slot 6. The slot 6 permits the clamps 8 to be adjusted inwardly or outwardly on the brackets 1 for adjusting the sections 7 toward or away from 80 the window frame 4. The arms 10 of the clamps 8 normally diverge toward their free ends. Thus, when said arms are drawn toward each other into clamping engagement with the flange 5 of the bracket 1, the loop or eye 9 is contracted in a 85 manner to grip or clamp the adjacent section 7. In other words, the ends of the loop or eye 9 are normally somewhat spread, in which position the arms 10 project in diverging relation and when said arms are drawn toward each other 90 similar movement is imparted to the end portions of the loop or eye. This construction permits the section 7 to conveniently be frictionally clamped in adjusted position.

Shade roller supporting brackets 12 are struck 95 out from the outer portions of the telescopic sections 7, said brackets 12 being of conventional construction. Also struck out from the telescopic sections 7 between the brackets 12 and the outer ends of said sections are curtain rod supporting 100 hooks or elements 13.

The construction and arrangement which has been provided is such that the sections 7, while being mounted on the sash 3 for vertical movement therewith, are disposed outwardly of the 105 window frame 4 and, as hereinbefore stated, said sections may be adjusted inwardly or outwardly on the brackets 1 through the medium of the clamps 8. Further, the sections may be conveniently adjusted longitudinally relative to each 110

other for various widths of windows or for other purposes and conveniently secured in adjusted position when the clamps 8 are secured to the brackets 1.

5 It is believed that the many advantages of a combined shade and curtain holder constructed in accordance with the present invention will be readily understood, and although the preferred embodiment of the invention is as illustrated and 10 described, it is to be understood that changes in the details of construction and in the combination and arrangement of parts may be resorted to which will fall within the scope of the invention as claimed.

15 What is claimed is:—
A fixture of the character described comprising

ing brackets, longitudinally slotted flanges projecting from the brackets, a pair of telescopic curtain pole sections, and clamps adjustably securing the sections on the brackets, each of said clamps being formed from a single length of resilient metal and including a split loop 80 encircling a section, the clamps further including normally diverging arms extending from the ends of the loops on opposite sides of the bracket flanges, and means extending through the arms of said clamps and the slots in said bracket flanges for adjustably clamping the arms to the bracket flanges.

FELIX P. LINDSAY.
